MUFFLE

Henry H. Harris, Champaign, Ill.

Application August 17, 1937, Serial No. 159,480

13 Claims. (Cl. 263—47)

My invention relates to muffles used in heat-treating furnaces, and particularly to a muffle or like container suspended or otherwise disposed within a furnace, the articles to be heat-treated being placed within the muffle or passed therethrough for treatment.

Conventional muffles are made of cast metal alloy, which renders them both heavy and expensive, since weight is a cost factor. It is the main object of my invention to make a light and relatively cheap muffle, and I accomplish this by making the muffle partly of cast alloy metal and partly of sheet alloy metal, preferably nickel-chromium-iron alloy metal or steel adapted to resist heat and corrosion.

It is also well known in heat-treating practice that sheet metal heats up and cools down much more quickly than does cast metal, and it is also an object of my invention to provide a muffle of cast and sheet metal, the parts of which are so connected that they will heat up and cool down at a fairly uniform rate, especially at and near regions where cast and sheet parts are interconnected.

Further objects of my invention will in part be obvious and in part specifically pointed out hereinbelow in connection with the following description of an illustrative embodiment.

In the drawing annexed hereto and made a part hereof,

Figure 1 is a transverse section through a conventional heat-treating furnace, and showing, also in section, one form of muffle constructed according to and embodying my invention, suspended therein;

Fig. 2 is a side elevation of the muffle, partly broken away and partly in section; and

Fig. 3 is a plan view of the muffle, with parts broken away.

Furnace 10 comprises side walls 12, 12 and arched roof 14, defining chamber 16 within which muffle 18 is suspended by means of chains 22, 22, secured to I-bars 24, 24, anchored in and through roof 14 by means of nuts 26, 26. Eye-bars 24, 24 are preferably angled with respect to each other to distribute the weight load over roof 14 and better support the muffle weight.

By suspending the muffle preferably from above, I am enabled to utilize the weight of the muffle and of its contents for holding the sheet portions thereof in a state of extension or semi-rigidity and to thereby dispense with need for braces, stiffeners, and the like, for the sheet metal portions. The drawing illustrates one way

of suspending a muffle within the furnace chamber, but this can be done in various ways.

The wall members of muffle 18 comprise cast portions 28, 28 and sheet portions 30, 32, of heat and corrosion resisting alloy metal. Cast portions 28, 28 form the upper corners of the muffle and are provided with upwardly extending ears 34, 34 to which the suspending chains 22, 22 are secured. The corner bars 28, 28 are preferably identical, and are provided with a central depression 29 with the inner and outer edges curving down and inwardly in a reverse direction from the depressed middle. In cross-section the curvature near the edges of bars 28 is almost semi-circular, and the ears 34, 34 are disposed in the central depression 29. Sheet 30 is welded on to the upper convex surfaces of the inner parts 36, 36, of bars 28, 28 to form the top wall of the muffle 10. A preferably continuous sheet 32 is welded to the convex outer surfaces of the other side portions 38, 38 of corner bars 28, 28, and serves in the form shown to form the sides and bottom walls of the muffle.

The floor 40 of the muffle is disposed within and supported by the side and bottom wall sheet 32. In forming the floor 40 a plurality of cross-beams 42 are disposed transversely within the muffle. Each beam 42 has a semi-circular notch 44 at the end thereof to receive a tube 46 extending lengthwise of the muffle. Tubes 46 are supported by the sheet wall member 32 and in turn support the cross-bars 42 and floor 40. Thus an extended rounded engagement is provided at 48 between sheet 32 and the outer rounded surfaces of tubes 46 to thereby avoid any possibility of producing a crack or break in the sheet member 32 at the region where it serves to support the floor 40.

The weight of the floor members and the contents of the muffle serves to put sheet 32 under tension, and this tension is taken up and absorbed by the curved surface weld connection 52. Thus the sheet wall parts 32 remain substantially rigid without reenforcing or bracing. Sheet 30, comprising the muffle roof or hood is under no particular tension other than its own weight, and may permissibly sag centrally, as shown.

The connections between cast and sheet members comprise broad overlaps as shown, and the welded connections are made at and near the edges of the sheet portions with the principal part of the overlap consisting of the sheet resting freely upon and in contact with a convex surfaced part of cast metal. The cast metal edges as 49

are turned in so as to face away from the sheet metal and not to contact the sheet, thus avoiding any injury to sheets from sharp edges of cast metal. The marginal parts of the sheets thus 5 heat up and cool off with the rounded cast metal with which they are in contact. Thus the welded joints between the cast metal and sheet metal are relieved from strains caused by uneven heating and cooling rates of thin sheet metal and 10 thicker cast metal as will be readily understood. When an extra-long muffle is desired, I weld together end to end a plurality of sections, as shown at 56. To keep the muffle from swinging within the furnace, and putting extra strain on the sus- 15 pending mechanism, as may occur in loading and unloading, I provide a pin or pins 58 on the underside thereof to be received within a track or channel (not shown) on the furnace floor. The floor 40 preferably contains the work-supporting tracks 40a.

20 My improved muffle is much lighter and cheaper than muffles made entirely of cast alloy, for example. Increased efficiency is secured by materially reducing the time required for the heat treatment operation, the sheet wall portions heating up rapidly and transmitting heat rapidly to the articles being treated.

I claim.

1. A muffle for use under suspension within 30 heat-treating furnaces comprising curved cast metal upper corner bars, and sheet steel top, side and bottom portions, said sheet metal portions being welded to the cast corner bars and also extending along and around the curved portions 35 of said bars.

35 2. A muffle as in claim 1 in which the cast steel corner bars curve inwardly of the muffle and the sheet portions overlie said curved cast portions.

40 3. A muffle as in claim 1 in which the edges of the cast bar portions curve away from the sheets, and the first points of contact between sheet metal and cast metal are removed substantially in from the edges of said cast bar portions.

45 4. A muffle as in claim 1 in which broad, rounded overlaps are provided where the cast and sheet metal portions meet, and the welding is at the extreme edge of the overlapping sheet portion around the curve of the corner bars.

50 5. A muffle for use in heat-treating furnaces comprising a pair of rigid, self-sustaining cast metal bar portions forming the upper corners of the muffle, a semi-rigid sheet metal portion welded thereto forming the roof of the muffle, and a second semi-rigid sheet metal portion 55 welded to said cast portions and forming the sides and bottom of the muffle.

60 6. A muffle as in claim 5 in which the cast metal upper corners are curved, and curve inwardly of the muffle.

60 7. A muffle for use under suspension within heat-treating furnaces comprising a pair of rigid,

self-sustaining cast metal bar portions forming the upper corners of the muffle, means secured to said cast upper portions whereby the muffle may be supported within a furnace, a semi-rigid sheet metal portion welded to said cast portions and forming the sides and bottom of the muffle, and means to place said second referred to sheet portion under tension.

8. In a heat-treating furnace comprising a floor, walls and roof, a muffle comprising a pair 10 of rigid cast metal bars forming the upper corners of the muffle, a semi-rigid sheet steel portion welded thereto forming the roof of the muffle, a second semi-rigid sheet steel portion welded to said cast portions forming the sides and bottom 15 of the muffle, and means to suspend said muffle within the furnace to permit the weight of muffle and contents to place said second semi-rigid sheet steel portion under tension and keep it from buckling.

20 9. A muffle as in claim 8 for use under suspension within heat treating furnaces in which the cast metal corner bars curve inwardly of the muffle and the sheet portions overlie said curved corners and are welded thereto at the extreme 25 edges of the overlapping sheet portions.

10. A heat-treating furnace as claimed in claim 8, in which the means to suspend said muffle comprises ears on said cast corner bars secured to chains and eyebars anchored in the roof of 30 the furnace, the chains and eyebars diverging upwardly from the muffle toward the roof.

11. In a heat-treating furnace comprising a floor, sides and a roof, a muffle comprising a pair of rigid, self-sustaining cast metal bar portions 35 defining the upper corners of the muffle, a sheet metal portion welded thereto forming the roof of the muffle, a second sheet metal portion welded to said cast bar portions and forming the sides and bottom of the muffle, means to place said first 40 referred to sheet metal portion under tension comprising a suspending connection of the muffle within the furnace, a floor within and supported by said second referred to sheet steel portion, the weight of the floor and muffle contents serving to keep said second sheet metal portion under tension.

12. In a heat-treating furnace as claimed in claim 11 wherein the transverse beams have notched ends, and a tube is disposed within said notches, which tube extends lengthwise of the furnace, whereby the second referred to sheet will pass around a curved edge.

13. In a muffle comprising a suspended sheet metal wall and bottom portion, a floor structure 50 within said sheet metal portion and said floor comprising round sectioned parts at its edges, and said floor being supported by said sheet metal portion by engagement thereof with the rounded edge portions.
